UNITED STATES PATENT OFFICE.

ADAM EMIL SCHATZ, OF MOUNT VERNON, NEW YORK.

APPARATUS FOR DISPENSING LIQUIDS.

1,112,386.

Specification of Letters Patent. Patented Sept. 29, 1914.

Application filed June 21, 1912. Serial No. 705,142.

To all whom it may concern:

Be it known that I, ADAM E. SCHATZ a citizen of the United States of America, residing at Mount Vernon, in the county of 5 Westchester and State of New York, have invented certain new and useful Improvements in Apparatus for Dispensing Liquids, of which the following is a specification.

My invention relates to improvements in 10 portable apparatus or receptacle for dispensing liquids under pressure, the latter being preferably provided with carbonic acid gas and has particular relation to an apparatus in which the gas container is 15 mounted on and removably connected to the receptacle having the liquid to be dispensed.

The principal object of my invention is to provide an apparatus in which there are two 20 chambers, one to convey the heavy charge and the other constituting a reducing chamber of smaller capacity to convey the charge of sufficient pressure to lift the liquid. This pressure should not exceed 25 pounds, for the reason that when the beer or liquid is 25 subjected to a greater pressure than say about 25 pounds, the liquid is so surcharged with the gas, that it will not flow freely, but will be discharged in a foaming condition. It is also very dangerous, to allow a heavy 30 charge of gas into the bottle as many have actually burst or exploded. By means of the reducing chamber this danger is entirely avoided.

A further object of my invention is to 35 provide an apparatus by means of which the gas container is charged through a port controlled by a valve of ordinary type or which may be charged by means of a capsule having carbonic acid gas, in which case the 40 head or gas container may be recharged without a special apparatus. The space formed between the walls of the container may be charged with hot or cold air, or the said spaces may be filled with asbestos or 45 other non-conducting material.

Another object is to provide an apparatus which is simple and efficient in operation, durable in construction, of sufficient strength to resist explosion, readily applied or re- 50 moved, and which may be manufactured at a relatively low cost.

The foregoing and such other objects as may occur from the ensuing description, are attained by the improved construction, combination and arrangement of parts herein- 55 after fully described and illustrated in the

accompanying drawings forming a part of this specification and particularly pointed out in the appended claims.

In the accompanying drawings in which 60 similar reference characters indicate similar parts in each of the views:—Figure 1, represents a central longitudinal sectional view of one form of my apparatus applied to a liquid container, showing the gas head or 65 chamber and a reducing chamber. Fig. 2, is a transverse sectional view taken on the line 2—2, Fig. 1. Fig. 3 is a detail view partly in section showing the means for actuating the valves shown in Fig. 1. 70

In the form shown in Figs. 1 and 2, I have 75 designed a container especially adapted for the use of tourists and automobilists, since they can be made of any suitable size, preferably of a gallon capacity. Persons traveling may always be provided with a cool or hot drink. For hospital use and in the sick room my improved containers are of great practical use.

As illustrated in Fig. 1 of the drawings, 80 a double vessel is shown. In this form the inner vessel may be of glass or where great strength is required may be made of metal, and for ease of manufacture, may be formed of two sections.

The numeral 1 indicates the inner vessel or bottle; 2 the outer shell; 3 the joints or laps when made of metal; 4 is the discharge siphon tube; 5 is the cushion placed between the two shells or vessels; 6 is a valve through 90 which hot or cold air may be forced in between the inner and outer shells or through which said air may be withdrawn; 7 is a screw-threaded upper portion or section of the outer vessel, to which is secured the 95 screw-threaded lower portion 8 of the casing 9 forming the reducing chamber 10, and seated in a recess formed in the lower portion of said casing 9, is a washer 11 against which the upper portion or neck of the inner vessel is adapted to rest. The upper portion of the casing is screw-threaded at 12 to which is secured the lower threaded end 13 of the head or main gas-chamber 14, the latter being provided with a screw-threaded 100 cap or cover 15 and a valved inlet 12* through which the chamber 14 may be filled with gas in case a capsule is not used. At one side of the chamber 14 is an outwardly 105 extended screw-threaded portion 16 and an inwardly extended portion 17 forming a chamber within which is placed the gas

charged capsule 18, said chamber being provided with a closure 19, the latter having an inwardly projecting portion 20 which serves to manipulate the capsule so as to discharge its contents, and 21 designates a gasket between the closure and capsule chamber to form a tight joint.

In the diaphragm 22 at the lower end of the chamber 14, is formed a valve seat 23, 10 normally closed by a valve 24, carried by a rod 25, the valve being normally positioned to close the seat 23, by means of a coiled spring 26 positioned on the rod 25, between an extension 27 formed on the inner end of 15 the casing of the capsule and the valve 24, the lower portion of the valve rod 25 extending into the smaller or reducing chamber 10. The latter chamber has a diaphragm 28 provided with a valve seat 29, said seat 20 being normally closed by a valve 30 provided with a valve stem 30^x extending upwardly into the chamber 10 and downwardly through the bottom portion 31 of the casing 9, said valve 30 being positioned on the 25 lower side of the valve seat and held seated by a coiled spring surrounding the valve stem between the lower portion of the said valve 30, and the bottom portion 31 of the casing 9. The bottom of said casing being 30 provided with an opening 32 through which the gas is admitted to the inner vessel. Extending through one side of the casing 9 and into the chamber 10 is a cam 33 carried by a rotatable key 34, the movement of said 35 cam in one direction opening the valve 24 and permitting the gas to pass into the lower or reducing chamber 10, and by moving the said cam in an opposite direction the valve 30 is opened, and gas thereby admitted to 40 the inner vessel, hence the lower end of the valve rod 25 and the upper end of the valve stem 30^x being on opposite sides of the cam, the said valves 24 and 30 may be operated successively but not simultaneously, as is 45 clearly shown in Figs. 1 and 4. By this latter construction communication between the inner vessel and the main gas-chamber 14 can only be had through the smaller or reducing chamber, the ports to which cannot 50 be opened simultaneously when the parts are in position.

It will be understood that the pressures in the two chambers need not be equal, that in the reducing chamber being simply the 55 pressure required to discharge the contents of the inner vessel, the pressure in the reducing chamber being increased by manipulating valve 24 when necessary.

In the form of the construction shown in 60 Figs. 1 and 2, the apparatus is so shaped and arranged as to rest on the side instead of the bottom. For securing this result, the members 1 and 2 have one side flat, while

the dispensing tube 4 is curved in the direction of its length to cause it to be properly positioned within the inner member 1, 65 said tube extending to the spout 14^x, the latter being located at the end of the main gas-chamber 14, instead of on the side. This structure of Figs. 1 and 2 being especially 70 useful in automobile service, affording a greater base support.

As will be readily perceived in the construction shown the receptacle and its head or pressure apparatus are complementally 75 formed so that the securing in position of the parts of the apparatus completely isolates the chamber surrounding the inner member of the receptacle, the securing operation firmly positioning the inner member 80 relatively to the outer member. Furthermore, the parts are arranged to permit of ready assemblage, and are of simple construction permitting of the formation of parts of maximum strength to resist usage 85 and liability of explosions.

Having thus described my invention what I claim and desire to secure by Letters Patent is:—

1. A liquid dispensing apparatus comprising a vessel, a gas head connected to said vessel having an upper main gas chamber provided with an auxiliary chamber formed in one side thereof for the reception of a gas charged capsule, a reducing chamber intermediate said main chamber and vessel, a valve connected with said main chamber, a valve connected with the reducing chamber, and means carried by the reducing chamber and extending within the same 95 for successively operating each valve to regulate the pressure supplied to the vessel 100 containing the liquid.

2. A liquid dispensing apparatus comprising a vessel, in combination with a gas containing head, said head having an upper main gas chamber provided with an auxiliary chamber formed in one side thereof for the reception of a gas charged capsule, a reducing chamber intermediate said main chamber and vessel, a valve connected with said main chamber, a valve connected with the reducing chamber, means carried by the reducing chamber and projecting into the same for successively operating such valves 115 to regulate the pressure applied to the vessel, and a discharge tube passing from the vessel entirely through the reducing chamber and main chamber and projecting through the top of the latter chamber.

In testimony whereof I here affix my signature in presence of two witnesses.

ADAM EMIL SCHATZ.
